UNITED STATES PATENT OFFICE.

JOHN A. ALEXANDER AND FRANK K. BERRY, OF BATTLE CREEK, MICHIGAN, ASSIGNEES TO A. B. STOVE COMPANY, OF BATTLE CREEK, MICHIGAN, A CORPORATION OF MICHIGAN.

GAS-RANGE.

1,060,573.

Specification of Letters Patent.

Patented May 6, 1913.

Application filed June 16, 1911. Serial No. 633,601.

To all whom it may concern:

Be it known that we, JOHN A. ALEXANDER and FRANK K. BERRY, citizens of the United States of America, residing at Battle Creek, in the county of Calhoun and State of Michigan, have invented certain new and useful Improvements in Gas-Ranges, of which the following is a specification, reference being had therein to the accompanying drawings.

It is the object of the invention to obtain an increased number of available burners on a gas range without increase in the size of the stove or the space limits which it occupies.

To this end the invention consists in the construction as hereinafter set forth.

In the drawings,—Figure 1 is a perspective view of a portion of a gas range to which our improvement is applied; Fig. 2 is a section through the elevated burner portions of the range.

A is the frame of a gas range, B is the open top or hot plate mounted on a portion 25 of said frame, and C is an oven mounted upon an adjacent portion thereof. As shown the open top section is of sufficient area for two burners D and E arranged in front and rear and provided with suitable 30 gas controlling valves G at the front.

To increase the number of burners without interference with those thus far described, and also without increasing the space limits necessary for the installation 35 of the range, we have provided an elevated burner H. This is arranged at the rear of the open top portion of the range and adjacent to the oven C. The burner H is positioned beneath and adjacent a shelf I which 40 is supported by a bracket J and rear wall K, the bracket being sufficiently cut-away to provide convenient access to the lower burner E. There is also provided below the shelf I and burner H, a lower shelf L 45 on which is supported the removable drip pan M.

Inasmuch as the burner H is arranged above the burner E it is evident that the draft created by the lower burner if permitted to find access to the upper burner, would interfere with the proper operation thereof. We have therefore guarded against this effect by placing a shield N in front of the shelf L with only a sufficient

opening for the removal of the pan M. 55 This guard or deflector N is preferably slightly inclined outwardly and upwardly and will thus direct the ascending air current from the lower burner E away from the burner H. It is however, necessary to 60 provide air for combustion in the burner H and this is accomplished by providing openings at the side or rear of the shelf. As shown, perforations O are formed in the bracket J and also in the rear wall K which 65 provide the necessary draft area for supplying the burner H with air.

With the construction as described all of the burners D, E and H may be used simultaneously without interference, and inasmuch as the burner H is below the plane of the top of the oven its presence does not increase the space occupied by the range.

What we claim as our invention is:

1. In a gas range, the combination with 75 a frame of an open-top burner mounted on a portion of said frame, an oven mounted on an adjacent portion of said frame, a second open-top burner positioned above the first-mentioned burner, a bracket extending 80 downward from said upper burner, and means extending between said bracket and said oven for shielding the upper burner from the draft created by the first-mentioned burner, there being a draft communication for said upper burner leading 85 to the space out of the path of the draft created by the first-mentioned burner.

2. In a gas range, the combination of the 90 frame, an open top burner mounted thereon, a hood extending upward from said frame and partially covering said burner, a shelf above said hood, a burner between said hood and shelf, and a shield for closing the front opening between said hood and shelf to exclude the draft from the lower burner.

3. In a gas range, the combination of the 95 frame, an open top burner thereon, a shelf above said open top burner, a hood for said open top burner forming a support for said shelf, a burner below said shelf, a shield below and a shield in front of said burner, said hood having draft openings for said upper burner, communicating with the space outside of said hood.

4. In a gas range, the combination with a 100 frame of an open top burner mounted on a portion of said frame, an oven mounted on

an adjacent portion of said frame, an upper burner positioned above the lower burner, a shelf for said upper burner, a wall extending from said shelf downward to said frame, a bracket extending from said shelf downward to said frame, and a shield for said upper burner extending from said bracket to said oven.

In testimony whereof we affix our signatures in presence of two witnesses.

JOHN A. ALEXANDER.
FRANK K. BERRY.
